UNITED STATES PATENT OFFICE.

NICOLAS GEORGEVITCH, OF PARIS, FRANCE.

IMPACT DEVICE.

Application filed May 12, 1923, Serial No. 638,575, and in France January 22, 1923.

This invention relates to a rotary impact device of the kind claimed in the specification of my United States application No. 611,884, dated the 10th day of January, 1923, and has for its object to devise improvements in the construction and arrangement of such devices which will improve their efficiency in operation and facilitate their manipulation.

10 The invention consists in an improvement in or modification of the impact device claimed in specification No. 611,884, dated the 10th day of January, 1923, characterized by the feature that the weights are restrained 15 and released by a cam device, guide members on the weights being adapted to contact with the cam device.

The invention also consists in other details and arrangements hereinafter described 20 and indicated.

The accompanying sheet of drawings illustrates solely by way of example a constructional form of this invention.

Figures 1 and 2 are respectively a section 25 on the line I—I of Figure 2, and a view, partly in section, on the line II—II of Figure 1 and partly in elevation of a rotary hammer worked by centrifugal force.

Figure 3 is a section on the line III—III 30 of Figure 1, of a portion of this hammer.

Figure 4 is a section on the line IV—IV of Figure 2, of a portion of this hammer, certain parts of the said hammer being shown in a different position.

35 Figure 4' is a section showing the joint between the levers 25 and 26 of Figures 1 and 4.

Figures 5 and 6 are respectively a section 40 on the line V—V of Figure 6, and a section on the line VI—VI of Figure 5, of an arrangement for controlling the rotation of the tool.

Figure 7 is a section on the line VII—VII of Figure 5 of a detail of this arrangement.

45 The rotary hammer worked by centrifugal force comprises a casing 1 having two flat ends 2 and 3 and a cylindrical wall 4, the flat walls 2 and 3 comprising annular bearing sockets 5 and 6 which are concentric with the said flat ends and in which a shaft 7 is mounted on ball bearings and ball thrust bearings.

50 On the shaft 7 there is fixed a member 8 comprising two symmetrical sockets 9, in each of which is mounted a weight 10. On the bearing 5 is mounted a plate 11 which

bears against the outer face of the wall 2, a cam 12 being pivoted at one end on a pivot pin 13 mounted in the plate 11, while the other end of the cam carries a stud 14 engaging in a slot 15 formed in the plate 11, having the shape of an arc of a circle and having its centre on the pivotal axis of the cam. Each weight is traversed by a rod 16 carrying a roller 17 which is adapted to come 60 into contact with the cam during the rotation of the shaft 7, the sockets 9 having apertures 18 for the passage of the ends of the rods 16.

The casing comprises a sleeve 19 in which 70 is mounted a tool holder mandrel 20, which comprises a collar 21 on which rests the end of a push-bolt 22. This bolt 22 is mounted in a socket 23 fixed to the sleeve 19. The casing is provided with a lug 24 on which 75 are pivoted a lever 25, one end of which rests upon the push-bolt 22, and a lever 26, one end of which bears against the cam 12. The two levers are connected by a pivotal joint which allows them a certain amount 80 of play. The shaft 7 receives its motion by suitable means, and during the rotation the weights are moved away from the axis of rotation by centrifugal force. When the weights reach the cam, they move nearer to 85 the axis of rotation, and on arriving at the end of the cam they are suddenly released, and strike with force the tool holder mandrel.

The plate 11 is provided with a rod 27 90 engaged in a slot 28 in the casing, which allows of shifting the plate angularly with the object of moving the cam nearer to or away from the tool holder sleeve, and at the same time of moving the end of the cam, 95 which carries the stud 14, nearer to or away from the axis of rotation. This device allows of so regulating the apparatus as to cause the weights to strike always upon the tool holder mandrel whatever may be the 100 speed of rotation of the shaft. The plate is held in any position in which it may be set by means of a suitable stop 29.

The member 29 is normally held in frictional engagement with the casing by means 105 of the spring which is shown in section in Figure 3, and while the member 29 can be withdrawn from engagement with the casing against the action of this spring to permit adjustment of the plate 11, it will when 110 released again contact with the casing and thus serve as a frictional stop to hold the

plate 11 in any position in which it may be adjusted.

The apparatus is provided with a handle 30 which can be held in one hand. This handle can be lengthened to such an extent as will enable it to be held with both hands at once by means of two extensions 31 arranged one on each side of the handle 30 in the prolongation of the latter, such extensions 10 being secured by means of a bolt 32 which extends through the handle and through the two extensions.

The apparatus is also provided with a bent rod pivoted to a lever 34, the axis of 15 which is mounted in a bracket 35 formed in one piece with the casing. This lever is in contact with a push-bolt 36 which is mounted in a socket 37 fixed to the sleeve 19 and is itself in contact with the collar 21. 20 The free end of the rod 33 is conveniently arranged along one of the extensions 31, and by exerting pressure upon this rod with the hand that holds the said extension, the operator moves down the push-bolt 36, which 25 by bearing upon the collar 21, causes the mandrel 20 to descend to a point where the push-bolt 36 is locked by a locking bolt 38 engaging in a recess 39 in the push-bolt 36.

The descent of the mandrel 20 allows of 30 the descent of the push-bolt 22, thus disengaging the latter from the lever 25, which in its turn ceases to act upon the lever 26. This lever 26 no longer exerts any pressure upon the cam 12 which is then pushed by the 35 weights against the cylindrical wall of the casing (Figure 4). The result of this new position of the parts is that the weights no longer strike the mandrel, and the hammer then revolves idly, this arrangement allowing of interrupting the work without stopping the motor.

In the case where it is desired that the apparatus should be able to work with a rotating tool, the said apparatus is provided 45 with a mechanism adapted to transmit the motion of the shaft 7 to the tool. This mechanism may, for instance, comprise a shaft 40 parallel to the axis of the mandrel and carried by a bearing 41 formed in one 50 piece with one of the flat sides of the casing. This shaft is connected to the tool 42 by means of gear 43, and on the shaft is mounted a pinion 44 provided with a stop-bolt 45 which allows of fixing the said pinion to the 55 shaft in two different positions according as this stop-bolt is engaged in one or other of two notches 46 and 47 formed in the shaft.

On the shaft 7 there is fixed a plate 48, 60 which is provided with holes 49 whose centres are spaced on a circumference concentric with the plate, the distance between the centres of two consecutive holes being equal to the pitch of the pinion 44, while the teeth 65 of the said pinion are adapted to engage in

the holes 49. The plate 48 comprises further two holes 50 which are of the same size as the holes 49 and are symmetrical relatively to the axis of the plate. The holes 50 are separated by two arc-shaped slots 70 51 having a width equal to the diameter of the holes 50 and terminating at their two ends in half circles whose centres are separated from the centres of the holes 50 by a distance equal to the pitch of the pinion 44. 75

When the stop-bolt is engaged in the notch 46, the teeth of the pinion 44 are in mesh with the holes 50 and slots 51. In this case, which is applicable to drilling machines, the plate drives the pinion only through the 80 length of one pitch at each half revolution of the pinion. Consequently the rotation of the pinion is intermittent. When the stop-bolt is engaged in the notch 47, the teeth of the pinion 44 are in mesh with the holes 85 49, and in this case, which is applicable to bores and to drilling machines, the rotation of the pinion is continuous. It will be understood that the pinion 44 is slideable upon the shaft 40 so that it may be displaced 90 by hand when necessary to cause it to mesh either with the holes 49 or with the holes and slots 50, 51. In order to permit of the disengagement of the pinion 44 from the wheel 48 for the purpose of enabling the 95 sliding adjustment to be made upon the shaft 40 the upper end of the shaft 40 should be moved outwardly (to the right in Figure 5) or if sufficient room be left for the purpose on the shaft 7 the wheel 48 may 100 be displaced inwardly (to the left in Figure 5) the movement in either case being sufficient to carry the tooth of the pinion 44 free of the wheel 48 before moving the pinion up or down.

Finally in the case of riveting machines, shapers and slotting machines, the pinion and the plate are out of engagement with each other, and consequently the tool does not rotate.

Having now described my invention what I claim as new and desire to secure by Letters Patent is:—

1. An impact device or hammer comprising a rotary shaft, a member fixed on the shaft and provided with a socket, a weight slidably mounted in said socket, said socket being slotted, a pin on the weight extending through said socket, a rotary guide on said pin and a cam cooperating with said guide for moving said weight against the action of centrifugal force and for suddenly releasing the same just before the moment of impact.

2. An impact device or hammer comprising a rotary member, an impact mass slideable radially thereof under the influence of centrifugal force, a guide member carried by said mass, a cam co-operating with said guide member for restraining the centrif-

ugal force and for suddenly releasing the same just before the moment of impact and means for throwing said cam out of action without stopping the machine.

- 5 3. An impact device or hammer comprising a rotary member, an impact mass slidable radially thereof under the influence of centrifugal force, a guide carried by said impact mass, an adjustable cam co-operating 10 with said guide for restraining the centrifugal force and for suddenly releasing the same just before the moment of impact and means for throwing said cam out of action without stopping the machine.
- 15 4. In impact device or hammer comprising a frame, a member mounted for rotat-

tion on said frame, an impact mass slidable radially of said member under the influence of centrifugal force, a guide member on said impact mass, a cam co-operating 20 with said guide member for restraining the centrifugal force and for suddenly releasing the same just before the moment of impact, and means for shifting said cam angularly of said frame for varying the point of release, said means comprising a plate rotatably mounted in said frame, said cam being carried by said plate.

In testimony whereof I have signed my name to this specification.

NICOLAS GEORGEVITCH.
